[57] CLAIM

The ornamental design for a vehicle tire, as shown and described.

DESCRIPTION

FIG. 1 is a side elevation view of a vehicle tire showing my new design, the opposite side being a mirror image thereof;

FIG. 2 is a front elevation view thereof; and

FIG. 3 is a perspective view thereof it being understood that the tread design is repeated uniformly throughout the circumference of the tire.

FIG.1

FIG.2

FIG.3
